CLAIM

The ornamental design for a mounting bracket sheet for RFID module, as shown and described.

DESCRIPTION

FIG. 1 is a front, bottom, and right side perspective view of a first embodiment of a mounting bracket sheet for rfid module showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is an enlarged view taken along with **8-8** lines of FIG. 2.

The broken lines illustrate portions of the mounting bracket sheet for RFID module which form no part of the claimed design.

The dot-dash broken lines illustrate a boundary that forms no part of the claimed design.

1 Claim, 8 Drawing Sheets(56)
